UNITED STATES PATENT OFFICE

NAT L. SOLOMON, OF BROOKLYN, NEW YORK

HAIR NET

Application filed September 30, 1930. Serial No. 485,341.

The invention relates in general to head gear and more particularly to hair nets.

An object of the invention is to provide a hair net which is substantially invisible, particularly at the point which crosses the forehead.

Another object of the invention is to provide a hair net having a binding band around a part of the periphery of the net but not at the part of the hair net which crosses the forehead.

Another object of the invention is to provide a hair net which is strong, durable and close-fitting, but not tight-fitting.

Other objects will be apparent from the following description and claims when considered with the accompanying drawings in which

Fig. 1 represents a blank or developed view of a complete hair net which is exaggerated or distorted to bring the entire net into the plane of the paper;

Fig. 2 is a front view of a completed net folded flat;

Fig. 3 is a side view of a completed net folded flat; and

Fig. 4 is a detail illustrating the manner of making the net.

In the following description and in the claims parts will be identified by specific names for convenience, but they are intended to be as generic in their application to similar parts as the art will permit.

Like reference characters denote like parts in the several figures of the drawings.

In the drawings accompanying and forming part of this specification, a practical commercial embodiment of the invention is shown, but as such illustration is primarily for purposes of disclosure, it will be understood that the structure may be modified in various respects without departure from the broad spirit and scope of the invention as hereinabove defined and claimed.

Referring now to the drawings and more particularly to Figs. 1 and 4, the net is made from a blank which comprises a body 10 of larger mesh and a banding 11 of smaller mesh. The front edge of the net indicated by 12 has no band but the band 11 is secured

at the sides 13, bevel edges 14 and back side 15.

A preferred way of making the net is to first form the body 10 from a strand of human hair or other suitable material. The strand is indicated by 16 in Fig. 4 and is first laid out in half meshes or V's to form the half-row A. The lengths of hair or other strand material are knotted together as at 17. After the first half-row A is laid out, say from right to left, the second half-row B of half meshes is formed, the strand being knotted at the points 18, as indicated, to form full meshes. After the half-row B is completed from left to right, the half-row C is formed from right to left, being knotted to the row B by knots indicated by 19. The end mesh indicated by 20 preferably is not formed until after the body 10 is completed when they are added for a purpose hereinafter described. Thus the entire body of the net is made by running the rows back and forth, as above described, as will be understood by those skilled in the art.

The width of the front edge 12 of the net body continues uniformly toward the back for a predetermined number of rows, forming the sides 13. Then the number of mesh in the horizontal rows drops uniformly to form the bevel edges 14 until the number of predetermined meshes is reached which forms the back edge 15. The number of meshes and the exact length of the sides 12, 13, 14 and 15 are determined by the shape of the finished net. In the present net disclosed for purposes of illustration only, the front row has 20 complete meshes, exclusive of the end meshes 20 and the back row at 15 has 8 complete meshes. The body of the net is outlined by the heavy line in Fig. 1 and the number of mesh in the horizontal rows is indicated by the numbers in circles. The rows of lesser meshes are made by catching two meshes of the preceding upper row by the lower row at two points such as at 40 near the ends of the rows.

The banding 11 extends from one end mesh 20 around the sides 13, 14 and 15, to the other end mesh 20, and is formed in a similar way to the rows of the body, except that the

- meshes are smaller and but 3 rows of half meshes are provided in this particular case, and the rows follow the perimeter of the body 10. If desired, when the banding 11 is added to the body 10, the perimeter of the 5 net is contracted to a certain extent. After the meshes are made, the net is fashioned to the shape shown in Figs. 2 and 3 so that when placed over the hair of the head, it will closely yet comfortably hold the hair in place.
- 10 The net becomes bonnet shaped as indicated in Fig. 3 and the shape is such that the binding effect on the head is uniform throughout the entire area of the net and substantially no greater at the edge of the net than at 15 points in the body.

Thus a hair net has been provided which is neat in appearance, strong and comparatively easy to make. The provision of the 20 extra end meshes 20 provides neat finishing ends for the banding of small meshes. The small meshes are used to hug the back of the head and hair above the nape of the neck and the bandless front edge 12 rests on the 25 forehead at the hair line, and having no band at this point provides a maximum degree of invisibility, which is of course very desirable.

It will be understood that the hair net above described is superior to the hair nets 30 now in common use, in which the banding meshes extend all the way around the net. In the hair nets heretofore known the banding is quite noticeable at the front of the net and also has a tendency to make the cap 35 quite baggy, which is undesirable with present coiffure styles, detracting from the neat and trim results expected by the user.

While certain novel features of the invention have been shown and described and are 40 pointed out in the annexed claims, it will be understood that various omissions, substitutions and changes in the forms and details of the device illustrated may be made by those skilled in the art without departing from the 45 spirit of the invention.

What is claimed is:

1. A hair net comprising a body portion 50 of relatively large meshes of uniform size and a perimetral band of smaller meshes extending partly around the perimeter of the body portion, said band comprising one or more rows, the unbandaged portion of the perimeter presenting the large body meshes only, thereby making this portion of the net of great 55 invisibility and relieving the strain of the banding.

2. A hair net comprising a body made up 60 of a plurality of meshes, a band of small banding meshes on a part only of the perimeter of the body, thereby to form a small cap to envelop the hair of the user.

3. A cap-shaped hair net comprising a 65 body having its front edge composed of large body meshes and a banding of smaller meshes extending around the body from the ends of

said front edge, the row at said front edge having an extra body mesh on each end to provide ends for the banding meshes whereby the small banding meshes are invisible from the front when the net is worn. 70

4. A hair net comprising body meshes and banding meshes extending around part of the body meshes only, thereby to form a cap which is self-conforming to the shape of the head. 75

5. A hair net comprising a series of body meshes having an extra end mesh at each end of the front row thereof and smaller banding meshes extending around the net from one 80 said extra mesh to the other, thereby leaving the front row free of banding meshes.

6. A hair net comprising a six sided blank, one side being the front side and being considerably longer than any of the other sides. 85

7. A hair net comprising a body portion 90 having a straight edge at the front, right and left side edges extending back at right angles from the front edge, right and left bevel edges converging from the back ends of said side edges, and a back edge parallel to said front edge connecting the back ends of said bevel edges, said body comprising large meshes running in rows parallel to said back and front edges, an extra mesh in the front row at each end thereof, a banding comprising 95 a series of rows of smaller meshes running from one said extra mesh around said side, bevel and back edges to the other extra mesh, said band adapted to contract to hold the net tight about the head, said front edge 100 being free of banding meshes.

8. A hair net comprising a body portion having a front edge side and back edges connecting said front edge, said body comprising large meshes running in rows parallel to 105 said back and front edges, an extra mesh in the front row at each end thereof, a banding comprising a series of rows of smaller meshes running from an extra mesh around said side, bevel and back edges to the other extra mesh, said band adapted to contract to hold the net tight about the head, said front edge 110 being free of banding meshes.

In testimony whereof I have hereunto set my hand. 115
